ATTORNEY

UNITED STATES PATENT OFFICE.

THOMAS MILLEN, OF NEW YORK, N. Y.

SIGN.

SPECIFICATION forming part of Letters Patent No. 626,791, dated June 13, 1899.

Application filed February 3, 1899. Serial No. 704,337. (No model.)

To all whom it may concern:

Be it known that I, THOMAS MILLEN, a citizen of the United States, residing at New York city, in the county and State of New York, 5 have invented an Improvement in Signs, of which the following is a specification.

This invention relates to street-car signs and their application. It has for its object to provide a means by which two or more 10 signs may be carried on one sheet of glass, with a movable shutter so arranged as to cover and obstruct the sign not in use, leaving that portion exposed to the light which is intended to announce the destination of the car, as 15 will be hereinafter explained.

In the accompanying drawings, which form a part of this specification, my invention is fully illustrated with similar letters of reference to indicate corresponding parts, as follows:

Figure 1 represents a face view exposing the upper portion of the glass sign, upon which the sign reads "East & West 59th Street," with the shutter *c* covering the lower portion 25 of the sign. Fig. 2 represents a face view also, showing the shutter *c* covering the upper portion of the sign and exposing the lower portion, which reads "9th Avenue." Fig. 3 represents an end view showing the shutter 30 *c* in its lower position and the frame *a* of the glass sign-plate *e* as it appears when resting within the bracket *d*. This figure also shows the button *h*, which hooks over the end of the frame *a* on the bracket *d* and holds the sign 35 in place. Fig. 4 represents a portion of the sign-plate *e*, showing part of the upper and lower inscription.

I would state that the mechanism marked *m* in the drawings and shown in Figs. 1 and 40 2 was patented to me on the 9th day of August, 1898, No. 608,616, and does not therefore form any part of the present invention.

In constructing my present invention it is intended to make the depth of the sign from 45 *s* to *w*, Fig. 3, the same as that between the roof and hood of the car to which it is to be applied, either on the side of the car or in front, in order that the light shining from within may be utilized to illuminate the sign 50 and make it conspicuous, the length of the

sign of course depending entirely upon the inscription which it is to contain.

The brackets *d* and *d'* are exactly alike, except that the bracket *d'* is provided with an overhanging piece *d''*, which carries the spindle of the revolving mechanism. This bracket is also provided with a vertical slot in its side, which acts as a guide for the clamp *u*. Therefore the description of the bracket *d* will answer for the description of the bracket *d'* 60 so far as its sign-carrying construction is concerned.

Referring to Fig. 3, the bracket *d* is provided with two vertical sides *f* and *g*, with a place between them sufficient for the introduction of the frame *a*, which carries the glass sign *e*. On top of the two side pieces *f* and *g* there is a small plate, as *i*, which extends crosswise and to which a roof of any desired size may be attached to protect the sign when 70 the latter is not placed under the roof of the car. On one side of the bracket *d*, as shown at *k*, a flat portion is provided, into which the shutter *c* is trunnioned, as at *c'*. This flat portion is provided with a brace, as *c''*, which 75 forms a part of the foot of the bracket and holds the upright portion in position. The key *e'* is passed through the trunnion *c''*, and a button, as *h*, is placed on the trunnion, and a suitable washer, as *h'*, on top of the button, 80 leaving the button free to be turned back or forth, as the case may require. On the opposite side of the bracket, as shown at *f'*, is a pin or rather a small hook projection, into which the button *h* rests when the sign is in 85 place. The object of this button is to close the opening in the bracket over the sign after it has been inserted to hold the latter in place.

The trunnion on one end of the shutter, as 90 shown at *l*, Figs. 1 and 2, is provided with a gear-wheel, which meshes with a suitable gear-wheel mounted on the upper end of the spindle *l'* of the reversing mechanism. Thus by turning the handle on the lower end of 95 the spindle, which is usually under the roof of the car and within reach of the conductor, the shutter *c* can be thrown either up or down to cover the lower sign or the upper one, as if the direction of the car should be "East 100

& West 59th Street" the shutter will be thrown down so as to cover the "9th-Avenue" sign. If the direction of the car should be "9th Avenue," the shutter will be elevated 5 so as to cover the "East & West 59th Street."

Having thus described my invention, what I claim, and desire to secure by Letters Patent of the United States, is as follows:

10 A railway street-car sign consisting of the slotted brackets *d* and *d'* provided with the projecting roof portion *i*, suitable transparent sign as *e* provided with two inscriptions and button as *h* for holding the sign in place, in

combination with the shutter *c*, trunnioned longitudinally between the said inscriptions 15 to the brackets *d* and *d'* and suitable mechanism as shown for elevating and lowering the said shutter to cover either of the said inscriptions, substantially as described.

In testimony that I claim the foregoing invention I have hereunto set my hand this 26th day of January, 1899.

THOMAS MILLEN.
